CARL PETERSON, OF ROSLINDALE, MASSACHUSETTS, ASSIGNOR TO GEORGE LAWRENCE, OF CAMBRIDGE, MASSACHUSETTS

SPRING-FORMING MACHINE

Application filed February 12, 1929. Serial No. 339,421.

My invention aims to provide improvements in spring-forming machines particularly adapted for forming spring leaf members.

5 In the drawings, which illustrate a preferred embodiment of my invention:—

Figure 1 is an elevation view of the spring-forming machine showing the quenching tank in cross-section and showing the 10 relation of the parts of the machine when a spring leaf is being tempered;

Fig. 2 is a part section and part elevation of one-half of the machine showing the relation of the parts when the spring bending 15 means is in position to remove a formed spring or receive a leaf to be bent;

Fig. 3 is a section taken on the line 3—3 of Fig. 2;

Fig. 4 is a section taken on the line 4—4 20 of Fig. 2;

Fig. 5 is a skeletonized view of the machine showing the relation of the parts after the spring leaf has been bent and before it is lowered into the quenching tank;

25 Fig. 6 is a cross-sectional view of the valve which controls the flow of fluid to the various cylinders and shows the valve in position to admit fluid-pressure to the cylinders to move the parts of the machine to the position shown in Fig. 2;

30 Fig. 7 is a view similar to Fig. 6, but showing the valve in position to admit fluid-pressure to the cylinders to move the parts of the machine to the position shown in Fig. 5; and

35 Fig. 8 is a view similar to Fig. 6, but showing the valve in position to cut off the fluid-pressure from the two outside cylinders and admit fluid-pressure to the other two cylinders to move the parts of the machine to the position shown in Fig. 1.

Referring to the drawings, I have shown 40 a spring forming and tempering machine which embodies certain features described and claimed in my co-pending applications Serial No. 125,113, filed July 26, 1926, Serial No. 234,126, filed November 18, 1927, and Serial No. 208,967, filed July 28, 1927.

45 The machine illustrated in Figure 1 includes a frame placed in an upright posi-

tion in a tempering tank 1 and having spaced I-shaped uprights 2 connected at their upper ends by top bars 3. These I-shaped uprights support cylinders 4 at their outer sides (Figs. 1, 2 and 5). Within each cylinder 55 I have provided a suitable piston 5 having a stem 6 extending downwardly through a stuffing box 7 at the lower end of the cylinder (Fig. 2) and connected to a crossbar 8. The crossbar 8 extends through slots 9 in 60 the I-shaped uprights (Fig. 2) and is attached at its ends to the stems 6, thereby being suspended in such a manner that it may move up and down with the pistons 5 with relation to the uprights 2. 65

The crossbar 8 may support form means of any suitable type to which a spring leaf may be shaped. However, I have preferred to illustrate the individually adjustable die members 10 in combination with the rack 70 and pinion and ratchet mechanisms all operable in the manner more fully described in my co-pending application Serial No. 125, 113 referred to above. With these die members 10 I may provide a form of any desired 75 shape to which I may bend a spring leaf.

Inside the two upright members 2 and above the crossbar 8 I have provided a second crossbar 11 having cylinders 12—12 secured to its ends, as shown in Figs. 1 and 80 2. Within each cylinder 12 I have provided a suitable piston 14 from which extends a stem 15 passing through a stuffing box 16 and having its other end attached to the crossbar 8, as best shown in Fig. 2. In this 85 manner the crossbar 11 is supported entirely by the crossbar 8.

The crossbar 11 may carry any type of 90 means for pressing a spring leaf to the shape of the form provided by the die members 10, but I prefer to show yieldable means 95 17 supported by rolls carried by brackets 17^a and having its ends secured to springs attached to the crossbar 11, as best shown in Figs. 1 and 2. The yieldable means and supporting structure is substantially the same in construction and operation as that shown and more fully described in my co-pending 100 application Serial No. 208,967 referred to above.

Upon the frame of the machine I have supported two sets of pulleys 18-18 (Figs. 1, 3 and 5) between the top bars 3 and single pulleys 19-19 at right angles to the pulleys 18-18 secured to the uprights 2 (Fig. 5) adjacent their lower ends. An endless belt or cable passes over these pulleys 19-19 and is secured to the crossbar 8 adjacent to both ends by clamps 20-20. By this pulley and cable arrangement I have provided means whereby I secure equal movement of both ends of the crossbar 8, thereby preventing any possibility of the crossbars becoming jammed between the I-shaped uprights 2-2 during their movement relative to the uprights.

In forming some spring leaves it is necessary to provide them with concaved portions near their ends (Fig. 1). Therefore, I have provided a pair of presser shoes 21-21 which are secured to the ends of threaded stems 22 (Figs. 2 and 4). The stems are supported in sliding blocks 23 mounted on the cross bar 11 and are adapted to be raised or lowered by turning the nut-like members 24 suspended from the blocks 23. The blocks 23 may be moved longitudinally along the crossbar 11 and clamped in place by tightening the nuts 25.

The central supporting part 26 has a threaded stem 27 slidable in a block 28 mounted in the crossbar 11 and an adjusting nut 29 is threadably attached to the stem for adjustment relative to the stem to provide a stop which will limit the upward movement of the part 29. This part 29 is adapted to press the yieldable means 16 against a spring leaf 41 and is particularly adapted to press the yieldable means and spring plate 40 into a central hollow in the form means whenever it is desirable to make a spring leaf with a central concaved portion.

Any suitable means may be used for conveying fluid-pressure to the various cylinders mentioned above, but, as the cylinders operate in pairs, I have shown (Figs. 1 and 5) a centrally located valve 30 secured to the top bars 3. There are three outlets from the valve casing and a main supply inlet. Each outlet feeds two tubes which lead to the cylinders.

The outlet 31 at the top of the valve casing branches into two flexible tubes 32 which connect with the lower ends of the cylinders 12. The outlet 33 branches into two tubes 34 which connect with the lower ends of the cylinders 4. The other outlet 35 branches into two flexible tubes 36 which connect with the tops of the cylinders 12.

The valve 30 (Figs. 6 through 8) has two ports 37 and 38 which lead from the central bore 39 with which the main supply inlet pipe 40 is connected. The ports 37 and 38 are adapted to register with the outlet in

the valve casing as and for the purposes more fully hereinafter described.

I will now describe the operation of my machine as it passes through the various stages of forming and tempering a spring leaf. Referring first to Fig. 2, I have shown the valve 30 turned so that the port 37 registers with the outlet 33 (Fig. 6) and the port 38 registers with the outlet 35, thereby admitting air or other fluid-pressure to the bottoms of the cylinders 4 and the tops of the cylinders 12. The parts assume the positions shown in Fig. 2 and the dies 10 may be adjusted to any suitable form. When the form is arranged, a spring leaf 41 (preferably heated) is placed on the dies 10, as shown in Fig. 2. Then the operator turns the valve 30 to the position shown in Fig. 7 to cut off the pressure supply to the outlet 35 and register the port 38 with the outlet 31, thereby admitting fluid-pressure to the bottoms of the cylinders 12 while the fluid-pressure remains on in the cylinders 4. As the bar 8 is held stationary and the pistons 14 and stems 15 are attached in fixed relation thereto, the fluid-pressure admitted to the lower ends of the cylinders 12 will move the cylinders 12 and crossbar 11, together with the yieldable element 17, toward the crossbar 8 and form means 10 to press the spring leaf 41 between the yieldable means 17 and dies 10, as shown in Fig. 5. In this Fig. 5, the shoes 21-21 are shown pressing the ends of the spring leaf 41 into the concaved portions provided by the form. By turning the valve 30 to the position shown in Fig. 8 the fluid-pressure will be cut off from the outlet 33 while remaining on in the outlet 31 leading to the bottoms of the cylinders 12. Thus, the spring leaf 41 will remain gripped between the forming means while the weight of the forming means and crossbars will pull the pistons 14 downwardly and allow the spring leaf to be immersed in the oil contained in the tank 1, as shown in Fig. 1.

After the spring leaf has been tempered, the valve 30 may be turned again to the position shown in Fig. 2 and the bars 8 and 11 will be raised from the tank 1 and spread apart to release the spring leaf.

The valve part 30 has a by-pass port 42 (Figs. 6, 7 and 8) which is adapted to register with the outlet 31 and an opening 43 in the valve casing (Fig. 6) to release the fluid-pressure from the bottoms of the cylinders 12. This same port 42 is also adapted to connect the outlet 33 with the opening 43 (Fig. 8) to relieve the pressure in the cylinders 4. A second by-pass port 44 is provided in the valve 30 to connect the outlet 35 with an opening 45 in the valve casing (Fig. 7), thereby to relieve the fluid-pressure in the tops of the cylinders 12.

At the top of each cylinder 4, I have pro-

vided a petcock valve 46 of well-known construction which provides means for regulating the escape of air from the upper sides of the pistons 5 and also to regulate the inlet of air, thereby governing the speed at which the pistons 5 will drop to lower the crossbars 8 and 11 into the oil tank 1.

5 Coil springs 47 are provided in the cylinders (Fig. 2) to cushion the pistons at the ends of their strokes.

10 Rolls 48 are attached to the crossbar 8 and bear against the cross-pieces of the I-shaped uprights 2 to guide the bar 8 in its up and down movement relative to the 15 frame.

15 While the cable acts to maintain the crossbar 8 in proper relation to the uprights 2, I have provided pivots 49, 50, 51 and 52, 20 between the cylinders 12 and crossbars 8 and 11, to permit relative movement between the parts, so that if one end of the bar 11 moves downwardly a greater distance than the other end the cylinders 12 will not bind 25 against the uprights. This unequal movement of the crossbar 11 might be caused by uneven adjustment of the screws 22 which carry the shoes 24.

20 The shoes 24 may be of different curvatures and, therefore, may be removably attached so that other shoes may be used according to the curvature of the concaved 30 portions desired in a spring leaf.

35 While I have illustrated and described a preferred embodiment of my invention, I do not wish to be limited thereby, as the scope of my invention is best defined by the following claims.

Claims:

40 1. In a spring-forming machine, a supporting structure, a part providing a form to which a spring leaf may be bent, said part being movable relative to said supporting structure, spring leaf pressing means mounted upon a part movable relative to said supporting structure to press a spring leaf against said form, and fluid-actuated means connecting said parts together and being operable to move one of said parts relative to the other to press a spring leaf between the form and the yieldable member.

45 2. In a spring-forming machine, a supporting structure, a part providing a form to which a spring leaf may be bent, said part being movable relative to said supporting structure, spring leaf pressing means mounted upon a part movable relative to said supporting structure to press a spring leaf against said form, fluid-actuated means connecting said parts together and being operable to move one of said parts relative to the other to press a spring leaf between the form and the yieldable member and means operable to hold one part stationary relative to the supporting structure while the spring leaf is being formed.

3. In a spring-forming machine, a supporting structure, a part providing a form to which a spring leaf may be bent, said part being movable relative to said supporting structure, spring leaf pressing means mounted upon a part movable relative to said supporting structure to press a spring leaf against said form, fluid-actuated means connecting said parts together and being operable to move one of said parts relative to the other to press a spring leaf between the form and the yieldable member and other fluid-actuated means connecting the supporting structure and one of said parts and being operable to hold one part stationary relative to the supporting structure when the spring leaf is being formed and being operable to move the two parts relative to the supporting structure.

4. In a spring-forming machine, a supporting structure, a part providing a form to which a spring leaf may be bent, said part being movable relative to said supporting structure, spring leaf pressing means mounted upon a part movable relative to said supporting structure to press a spring leaf against said form, fluid-actuated means operable to move one of said parts relative to the other to press a spring leaf between the form and the yieldable member, said fluid-actuated means comprising a cylinder secured to one of said parts and a piston operable in the cylinder and secured to a stem attached to the other of said parts.

5. In a spring-forming machine, a supporting structure, a part providing a form to which a spring leaf may be bent, said part being movable relative to said supporting structure, spring leaf pressing means mounted upon a part movable relative to said supporting structure to press a spring leaf against said form, fluid actuated means connecting said parts together and being operable to move one of said parts relative to the other to press a spring leaf between the form and the yieldable member, and other fluid-actuated means operable to hold one part stationary relative to the supporting structure when the spring leaf is being formed and being operable to move the two parts relative to the supporting structure, said other fluid-actuated means comprising a cylinder secured to said supporting structure and a piston operable within the cylinder and secured to a stem attached to the part which carries the part which provides the form means.

6. In a spring-forming machine, a frame having spaced upright members, a crossbar slidable vertically relative to said upright members, form means carried by said crossbar, a second crossbar spaced from said first crossbar and slidable vertically relative to said upright members, means carried by said second crossbar for pressing a spring

leaf to the shape of said form means, means connected directly with said crossbars whereby one may be moved relative to the other, and fluid-actuated means connected between the frame and one of the cross-bars whereby the crossbars may be moved as a unit relative to the upright members.

7. In a spring-forming machine, a supporting structure, a bar slidable relative to said supporting structure, a number of pulleys secured to said supporting structure, a continuous cable passing over said pulleys and connected to the bar adjacent its ends, said cable providing means for maintaining alignment of the bar with relation to the supporting structure, a second bar connected directly to said first bar, means operable to move said bars together or separately and spring bending and forming means carried by the said bars.

8. In a spring-forming machine, a supporting structure, a bar slidable relative to said supporting structure, a number of pulleys secured to said supporting structure, a continuous cable passing over said pulleys and connected to the bar adjacent its ends, said cable providing means for maintaining alignment of the bar with relation to the supporting structure, a second bar, fluid-actuated piston means connecting the bars and providing the only means for supporting the second mentioned bar, and spring bending and forming means carried by the said bars, said fluid-actuated piston means operable to move one bar relative to the other as and for the purposes described.

9. In a spring-forming machine, a supporting structure, a bar slidable relative to said supporting structure, a number of pulleys secured to said supporting structure, a continuous cable passing over said pulleys and connected to the bar adjacent its ends, said cable providing means for maintaining alignment of the bar with relation to the supporting structure, a second bar, fluid-actuated piston means connecting the bars and providing the only means for supporting the second mentioned bar, and spring bending and forming means carried by the said bars, said fluid-actuated piston means operable to move one bar relative to the other as and for the purposes described and fluid-actuated piston means connected between the supporting structure and the first mentioned bar to provide for movement therebetween.

10. In a spring-forming machine, a frame having spaced upright members, a crossbar slidable vertically relative to said upright members, form means carried by said crossbar, a second crossbar spaced from said first crossbar and slidable vertically relative to said upright members, means carried by said second crossbar for pressing a spring leaf to the shape of said form means, cylinders

attached to said uprights, pistons operable within said cylinders by fluid-pressure stems extending from said pistons and said first mentioned crossbar being suspended by said stems and movable therewith, cylinders secured to the ends of the second mentioned crossbar and having pistons operable therein by fluid-pressure, said last mentioned pistons being connected by stems to said first mentioned crossbar as and for the purposes described.

11. In a spring-forming machine, a frame having spaced upright members, a crossbar slidable vertically relative to said upright members, form means carried by said crossbar, a second crossbar spaced from said first crossbar and slidable vertically relative to said upright members, means carried by said second crossbar for pressing a spring leaf to the shape of said form means, cylinders attached to said uprights, pistons operable within said cylinders by fluid-pressure stems extending from said pistons and said first mentioned crossbar being suspended by said stems and movable therewith, cylinders secured to the ends of the second mentioned crossbar and having pistons operable therein by fluid-pressure, said last mentioned pistons being connected by stems to said first mentioned crossbar as and for the purposes described and a movable flexible connection between the frame and the first mentioned crossbar to provide means for maintaining the crossbars in alignment with the frame.

12. In a spring-forming machine, a supporting structure, a crossbar carried by said supporting structure, for means carried by said crossbar and providing a form to which a spring leaf may be bent, a second crossbar, spring leaf pressing means carried by said second crossbar for pressing a spring leaf against said form and fluid-pressure operated piston means connected directly between said crossbars, thereby to act upon said form means and spring leaf pressing means to press a spring leaf between them.

13. In a spring-forming machine of the class described, a crossbar 8 and a crossbar 11, a series of independently adjustable elements 10 carried by the crossbar 8 and providing a form to which a spring leaf is to be bent, a yieldably mounted member 17 carried by the crossbar 11, a central presser member 26 loosely mounted for transverse sliding movement relative to the crossbar 11 and adapted to press the member 17 against the central part of the form provided by the elements 10 and two presser members 21 adjustable transversely relative to the crossbar and also longitudinally adjustable relative to the crossbar 11, as and for the purposes illustrated and described.

14. In a spring-forming machine of the class described, a frame having two upright

members 2—2, a crossbar 8 slideable relative thereto, a second crossbar 11 slideable relative to the uprights, fluid-pressure operated means secured between the frame and the crossbar 8 for moving the crossbar, other fluid-pressure operated means connected directly between the crossbars 8 and 11 for operating the crossbar 11 relative to the crossbar 8, cable means suspended on pulleys 18 and 19 mounted upon the frame, said cable means being connected to the crossbar 8 to maintain equal movement of the ends of the crossbar 8 with relation to the uprights 2 and pivot connections 49, 50, 51 and 52 between the second mentioned fluid-pressure means and the crossbars 8 and 11, all as and for the purposes described.

In testimony whereof, I have signed my name to this specification.

20 CARL PETERSON.
